HENRY D. JAMES, OF PITTSBURGH, PENNSYLVANIA, ASSIGNOR TO WESTINGHOUSE ELECTRIC AND MANUFACTURING COMPANY, A CORPORATION OF PENNSYLVANIA.

STARTING APPARATUS FOR ELECTRIC MOTORS.

1,175,358.

Specification of Letters Patent.

Patented Mar. 14, 1916.

Application filed February 21, 1911. Serial No. 609,943.

To all whom it may concern:

Be it known that I, HENRY D. JAMES, a citizen of the United States, and a resident of Pittsburgh, in the county of Allegheny 5 and State of Pennsylvania, have invented a new and useful Improvement in Starting Apparatus for Electric Motors, of which the following is a specification.

My invention relates to automatic devices 10 for progressively short circuiting or cutting out resistance which is primarily included in the circuit of an electric motor, and it has for its object to provide a control apparatus in which a plurality of switches are 15 connected to the respective sections of a resistor and are provided with means for regulating the short circuiting of the resistor sections, as the electromotive force of the motor builds up and the current cor- 20 respondingly decreases, which shall be operative without the employment of relays or interlocking connections.

The single figure of the accompanying drawing is a diagram of a motor and con- 25 trol circuits constructed and combined in accordance with my invention.

The energy for operating the motor 1 of the system shown is supplied from conductors 2 and 3, through fuses 4 and 5 and 30 a manually operated switch 6. Normally connected in series with the armature 7 and series field magnet winding 8 of the motor 1 is a resistor 9 comprising three sections 10, 11 and 12 which are successively and 35 automatically short circuited by means of switches 13, 14 and 15, the stationary contact terminals 16, 17 and 18 of the several switches being connected to suitably spaced points in the resistor in order to coöperate 40 with movable contact terminals 19, 20 and 21 in successively short circuiting the resistor sections at such points. The movable contact terminals 19, 20 and 21 are permanently connected in series with each other 45 and to one terminal of the resistor 9 and also to one terminal of the shunt winding 22 of the motor 1. Each of the stationary contact terminals is connected through an operating coil 23 of the switch to which it 50 belongs, to one terminal of the shunt field magnet winding 22 and to one terminal of the armature 7 of the motor 1.

The switches 13, 14 and 15 are severally

provided with coils 24 that are wound to act in opposition to the operating coils 23 and are connected in series with each other from the supply conductor 3 to the terminals of the resistor and the shunt field magnet winding of the motor 1 which are connected together. 60

Each of the movable contact members 19, 20 and 21 of the switches 13, 14 and 15 is connected to and operated by a core or armature 25 which is subjected to the magnetic field produced by the corresponding coil 23. A core or armature 26 for the corresponding coil 24 is connected to the core or armature 25 and an adjustable armature or core 27 is also provided in order to adjust the force exerted by the coils 24 in opposition to that exerted by the closing coils 23.

The closing coils 23 are connected in multiple circuit relation with different proportions of the resistor 9 included in the 75 circuit branches, consequently the potential at the terminals of the several coils is unequal and these coils may be uniform in construction and will tend to close the switches in a predetermined sequence. The 80 actual time at which each switch is closed and the time intervals between the closure of the switches may be varied as desired by adjusting the core members 27 which are influenced by the opposing coils 24. It is 85 therefore evident that the sequential closure of the switches is primarily independent of the adjustable cores and that the latter are provided for the purpose of adjusting the forces exerted by the opposing coils. 90

In the operation of the apparatus herein-before described, when the switch 6 is closed to start the motor 1, the counter-electromotive force of the motor will be a minimum and, consequently, the principal resistance to the flow of current through the motor will be exerted by the resistor 9, and the current which flows through the motor and the resistor will also flow through the opposing series coils 24. As the counter- 95 electromotive force of the motor increases with its increased speed, the electromotive force to which the coil 23 of the switch 13 is subjected increases until the pull which is exerted upon the core 25 by the 100 coil 23 exceeds that which is exerted upon 105

the core 26 by the coil 24, and thus closes the switch 13 to short circuit the resistor section 10.

As the counter-electromotive force of the motor 1 continues to build up, the electro-motive force, to which the coil 23 of the switch 14 is subjected, increases until the switch 14 is closed, to short circuit the resistor section 11. As the counter-electromotive force of the motor 1 increases still further with its increase in speed, the increased electro-motive force upon the coil 23 and the diminished current in the coil 24 of the switch 15 will cause the said switch to close and short circuit the resistor section 12, thus removing all of the starting resistance from the motor circuit. The number of resistor sections and the number of switches may, of course, be different from what I have shown.

It will be understood from the foregoing description that the parts may be so proportioned and adjusted that the switches will so operate to short circuit the resistor sections as to effect the starting operation without the utilization of any relays or interlocking devices for the purpose of insuring sequential operation.

I claim as my invention:

1. A control system comprising an electric motor, a starting resistance connected in series therewith, a plurality of switches for excluding the resistance step by step, similar closing coils for the several switches connected across the motor circuit in multiple relation with one set of corresponding terminals connected to different points in said starting resistance whereby the switches tend to close sequentially, a core member on each switch influenced by its closing coil, a plurality of opposing coils for the several switches connected in series relation in the

motor circuit and an independent adjustable core member for each switch influenced by the opposing coil pertaining thereto.

2. A control system comprising an electric motor, a starting resistance adapted to be connected in series therewith, a plurality of switches for excluding the resistance step by step, closing coils for the several switches, connected across the motor circuit in multiple relation, a different proportion of said resistance being included in each branch whereby the switches tend to close sequentially, a plurality of opposing coils for the switches connected in series relation in the motor circuit and an adjustable magnetizable core member influenced by each opposing coil.

3. A control system comprising an electric motor, a starting resistor in series therewith, a plurality of switches for excluding said resistor step by step, means for closing said switches in sequence in accordance with the counter electromotive force values of said motor, said means comprising a series of uniform coils connected across the motor circuit in multiple relation with one set of corresponding terminals connected at different points in said starting resistor, means for opposing the closing of said switches in accordance with the current traversing said motor circuit, said means comprising a plurality of coils in series with said motor, and adjustable means for varying the effect of said series coils.

In testimony whereof, I have hereunto subscribed my name this 31st day of Jan. 1911.

HENRY D. JAMES.
